UNITED STATES PATENT OFFICE.

DAVID H. HODES, OF NEW YORK, N. Y.

WEARING APPAREL.

Application filed January 27, 1922. Serial No. 532,135.

To all whom it may concern:

Be it known that I, DAVID H. HODES, a citizen of the United States, residing in the city, county, and State of New York, have 5 invented certain new and useful Improvements in Wearing Apparel, of which the following is a specification.

This invention relates more especially to wearing apparel which may be adapted at 10 will for summer or winter use.

One of the objects of the present invention is to provide an improved construction, combination and arrangement of parts in a vest which may be converted at will from a 15 closed to an open back or vice versa. A further object is to provide an improved construction which will obviate the discomforts usually attending the use of vests of this character or in the use of vests with closed 20 backs. Among other objects, this invention contemplates a construction which will adapt a skeleton vest or similar article of wearing apparel to retain its shape in position 25 on the wearer. The invention contemplates an article of wearing apparel which will afford a maximum degree of 30 relief from the summer heat, present a neat appearance, and when desired, have the appearance of a vest made in the usual conventional style. A specific object of invention 35 is to provide suitable means for imparting a tendency to the vest to conform to the person of the wearer and for supporting those portions of a skeletonized vest which would otherwise get out of shape and present an untidy appearance.

Another object of the invention is to provide an improved construction for vests having a detachable back and improved 40 means for imparting a snug fit to the person of the wearer whether the detachable back be in use or not.

Other and further objects will appear in the specification and be pointed out in the 45 appended claims, reference being had to the accompanying drawings which show a preferred embodiment of my invention.

In the drawings:—

Figure 1 is a plan view of the vest front 50 with the side and back straps omitted;

Figure 2 is a plan view of the detachable back of the vest;

Figure 3 is a sectional view of the complete vest, portions of the front sections being 55 broken away;

Figure 4 is a side elevation of the vest with the back detached;

Figure 5 is a rear elevation of the vest in position on the wearer; but with the back detached;

Figure 6 is a fragmentary inside elevation of the rear edge of one of the front sections of the vest, parts being broken away to show the interior construction;

Figure 7 is a detail cross-section of the 65 same;

Figure 8 is a vertical section thru the apparel from front to back with the detachable back in position;

Figure 9 is an inside elevation of a vest 70 with an open back;

Figure 10 is an elevation of a modified form of the detachable back shown in Figures 8 and 9.

Referring more particularly to the drawings, the front sections 1 and 2 of the vest merge into a neck portion 3. In order to provide suitable means for sustaining the front sections 1 and 2 of the vest so as to prevent the formation of creases and wrinkles, strips 4 of suitable resilient material such for example as whalebone or spring metal or the like are arranged to extend from top to bottom of the rear edges of said front sections. Said resilient strips 80 4 are adapted in connection with suitable stays or straps to be presently referred to, to maintain the rear edges of said front sections 1 and 2 in snug fitting relation to the person of the wearer and at the same time 85 to afford a more substantial support for the fastening means whereby the detachable back may be applied thereto. For this latter purpose I provide suitable means such for example as snap fasteners 5 arranged in vertical series along the rear edges of the front sections and in suitable positions to be connected up with complementary snap fasteners 6 arranged along the forward edges of the detachable back 7. Similar 90 devices on the neck piece 3 may be adapted to receive complementary fasteners 9 arranged along the top of the detachable back 7. As shown in Figures 5, 6, and 7, the 95 resiliently supported rear edges of the front parts 1 and 2 are connected by a waist band strap 10, while a pair of oblique shoulder straps 11 and 12 extend from the upper end of the resilient strips 4, to the collar piece 3, being preferably connected thereto beneath 100

105

110

the outer fasteners 8 on said collar piece. A vertically arranged strap 13 extends from the middle of waist strap 10 and is secured to the collar piece 3 preferably beneath the 5 middle fastener 8. As shown in Figure 7, the resilient strip 4 on either side may conveniently be arranged between the rear edge of the fore-part of the vest and a strip of lining 14 extending along said rear edge, 10 the strap 10 being secured at one end to said lining strip. According to the complete vest shown in Figures 8 and 10, the detachable back 15 is provided with an opening 16, said back being provided with suitable snap fasteners 17 which are adapted to detachably engage complementary fasteners 18 mounted along the resilient strips. According to the embodiment of my invention shown in Figure 9, the front sections 20 and 15 20 of the vest are provided with resilient strips 22 and 23 which are arranged on opposite sides of an opening 24 in the back 25 of the vest, thus affording suitable support to the material on opposite sides of 25 said opening and serving to retain the shape of said vest. The method of using and the constructional advantages of my improved vest will be readily understood and briefly related are as follows. In warmly heated 30 houses or in summer time when the temperature is relatively high, the wearer may provide himself with a vest of the lightest possible construction and neat in appearance. At the same time the self-sustaining structure embodying the resilient strips supported at their lower ends from the waist line 35 and suspended at their upper ends from the collar piece by means of oblique straps, conduces to the comfort of the wearer by eliminating the usual drawing or binding effects 40 of the vest in the back. At times when it may be desired to increase the warmth of the apparel the detachable back 7 will be readily attached at the will of the wearer to form 45 a closed back. Furthermore, this construction affords ready means for attaching replaceable backs of different weights and texture.

I claim:

- 50 1. An article of wearing apparel provided with a collar piece and an opening in the back thereof, resilient means for supporting the material along the edges of said opening, a back section detachably connected to said collar piece, and means for detachably connecting said back section to the resiliently supported material along the edges of said opening for supporting the material from said collar piece.
- 55 2. An article of wearing apparel provided with a collar piece and an opening in the back thereof, means for resiliently supporting the material along the edges of said opening, a back section detachably connected to said collar piece, and means for de-

tachably connecting said back section to the resiliently supported material along the edges of said opening for supporting the material from said collar piece, said back section being provided with an opening 70 therein.

3. An article of apparel comprising front sections stiffened along the rear edges thereof and merging above into a collar piece, said article of apparel being provided with a 75 connecting strap extending across the back of the wearer for connecting the stiffened rear edges of said front sections and oblique straps extending from said stiffened rear edges of the front sections to said collar 80 pieces.

4. A skeleton vest comprising front sections merging above into a collar piece, said front sections being provided with means for resiliently supporting the rear edges 85 thereof, a waist strap extending around the back of the wearer between the resiliently supported rear edges of said front sections, oblique straps extending from the upper ends of said resiliently supported edges to 90 said collar piece, and a vertical strap extending from said collar piece to the middle of said waist strap.

5. An article of wearing apparel comprising front sections merging into a collar piece 95 and provided with resilient strips extending along the rear edges thereof, a waist strap connecting the rear edges of said front sections and extending from one resilient strip to the other adjacent the bottom ends thereof, and oblique straps extending from adjacent to the upper ends of said resilient strips to said collar piece.

6. An article of wearing apparel comprising front sections merging into a collar piece 105 and provided with resilient strips extending along the rear edges of said front sections, a waist strap connecting the rear edges of said front sections and extending from one resilient strip to the other adjacent the bottom ends thereof, oblique straps extending from the collar to the rear edges of said front sections adjacent to the upper end of 110 said resilient strips, and a vertical strap extending from said collar to the middle of said waist strap, said articles of wearing apparel being provided with a back section adapted to be detachably connected to the front sections along said resilient strips and above to said collars.

7. An article of wearing apparel provided with oppositely arranged front sections and with an open back, a collar piece connecting said front sections, and a back section detachably connected to said collar piece, 125 means for detachably connecting the forward edges of said back section to the rear edges of said front sections for supporting the latter from the former.

8. A skeleton vest comprising front sec- 130

tions merging above into a collar piece, detachable fasteners arranged along said collar piece, said front sections being provided along the rear edges thereof with resilient supporting means, detachable fasteners arranged in vertical series along the resiliently supported rear edge of each of said front sections, a strap connecting the lower ends of said resiliently supported edges of said front sections, a strap connecting the upper end of the resiliently supported edge of each front section to said collar piece, and a detachable back provided with suitable fasteners for releasably engaging the fasteners on said collar piece and on each of the resiliently supported rear edges of said front sections. ¹⁵
